STACKER TUBE FOR CONE CUP MACHINE

Paul H. Carter, Baltimore, Md., assignor to
Joseph Shapiro, Baltimore, Md.

Application November 2, 1955, Serial No. 544,492

5 Claims. (Cl. 193—2)

This invention relates to paper cup making machines and is more particularly concerned with an improvement in certain types of paper cup making machines which utilize a stacker tube.

In the manufacture of the so-called "cone" or V paper cups, a number of different types of machines are employed. Basically, however, these machines comprise a cone-shaped mandrel about which a piece of paper is wound to form the cup. Prior to winding the paper about the mandrel, glue is applied to the paper at selected areas so that the cup after it is formed will hold its shape and be leakproof.

Cups of this type, in order to be profitable from the point of view of the manufacturer, must be made at an extremely rapid rate of production and they are frequently made as fast as 200 to 300 cups per minute. This means that each cup is on the mandrel only a fraction of a second. To date, no one has yet devised a glue suitable for use on such cups which sets in such a short period of time. Accordingly, it is necessary to hold the cups, after they leave the mandrel, in a conical shape for a period sufficient to permit the glue to set. This is frequently done by means of a stacker tube into which the cups are projected serially from the mandrel. As the cups pass slowly from one end of the stacker tube to the other, their shapes are retained while the glue sets and they can then be removed without danger of opening up or leaking.

A typical stacker tube is illustrated in U. S. Patent No. 2,203,513 which is inclined downwardly at its receiving end and provided with opposing ratchet toothed or barbed members which permit the cups to pass into the tube point first, but restrain them from moving in the opposite direction.

Another type of stacker tube is shown in U. S. Patent No. 2,203,510 wherein an oscillating stacker plate is provided to hold the cups in place.

By an exacting stroboscopic examination, I have found that stacker tubes of these and similar types which utilize a member in contact with the mouth of the outermost cup or cups have certain disadvantages. In the case of the ratchet-toothed or barbed members, for example, the flexing of the rim of the cup is of a decided disadvantage. As indicated above, the glue at this point in the operation of the machine has not yet had time to set. Accordingly, the flexing of the cup or the application of a force against the rim of the cup, has a tendency to cause the cup to open up along the glued seam thereof, or to cause a shifting of one edge over the other at the glued areas, particularly near the rim of the cup. As a result, some of the cups may become damaged, or some of the glue may be spread to an exterior or exposed area and cause sticking with an adjacently nested cup.

The general object of this invention is the provision of a stacker tube of the type mentioned which does not employ and does not require the use of any form of barb or detent to hold the cups in the stacker tube.

Another object of the invention is the provision of a

2

stacker tube of the type mentioned having a throat section so designed as to obviate the flexing of the cups thereby.

A further object of the invention is the provision of a stacker tube which has a throat section with a smooth interior surface and means for preventing the building up of air pressure between a cup entering the tube and the stack of nested cups already in the tube.

These and other objects and advantages of the invention will be apparent and more fully understood from the following description considered together with the accompanying drawing.

In the drawing:

Fig. 1 is a side elevational view of an embodiment of the invention shown attached to a form of cup-making machine, partly in section.

Fig. 2 is a view of the stacker tube, on a larger scale, apart from the cup-making machine and partly broken away.

Fig. 3 is a developed view of the upper part of the stacker tube.

Fig. 4 is an end view of the stacker tube looking down the throat thereof.

Referring with more particularity to the drawing in which like numerals designate like parts, the embodiment illustrated is shown in combination with a typical cone-forming machine of the type described in U. S. Patent No. 2,287,015, and having a forming mandrel 11, a bottom plate 12, a knife edge 13 on the mandrel 11. A paper strip (not shown) is supported by the plate 12. There is also a mandrel shaft 14, driven by a suitable source of power, gears 15 on shaft 14 engaging an idler gear 16 on a shaft 17 which is also engaged with a gear 18 on a vertical spindle 19. A casting 20 supports the entire mandrel assembly which revolves around the spindle 19.

The entire mandrel assembly, including casting 20, is rotated in an orbital path by a suitable source of power (not shown) and is supported by means of a stationary head 21.

To the lower part of the vertical spindle 19 is affixed a housing 22 upon which is mounted a rotatable wheel 23, hereinafter referred to as the discharge or kick-off roll. When the mandrel is in discharge position, as shown in full lines in Fig. 1, the completed cup thereon is brought against the rapidly rotating wheel 23 and is thereby discharged into the stacker tube 24 mounted in the general position shown in Fig. 1.

The cups move off the mandrel into the mouth of the stacker tube with such rapidity that there is an air pressure built up on the exterior of the cups as they move. In ordinary types of stacker tubes, this air pressure is retained and it develops between the cup going into the tube and the nested stack already in the tube. As a result, there is a tendency for the cups to jump back out of the mouth of the tube until the pressure is released by leakage of air past the rim of the incoming cup. To prevent this, various means have been provided in prior types of stacker tubes, including barbed members, oscillating pressure plates, etc. In accordance with this invention, however, all such mechanical holding means with their inherent functional defects, as explained above, are eliminated and instead, there are provided means to avoid or sharply reduce the air pressure build up. Such means include a front section on the stacker tube having a group of outwardly flared fingers 25 spaced apart by means of wedge-shaped slits 26. The throat of the tube which is immediately adjacent said fingers is also provided with apertures 27, preferably in a circumferential row, as shown.

By these means, air cannot become trapped between the nested stack and the incoming cups, because the space

thereof is in communication with the exterior through the apertures 27 and the slits 26. The flaring of the fingers 25 also provides a better target for the cups as compared to the type of stacker tube in which the mouth end is substantially of the same diameter as the rim of the cups. This means that the cups are cammed into the stacker tube by the flared fingers rather than by the sloping sides of the cups. Moreover, the flaring of the fingers plus the vents 27 and slits 26 obviate a flexing of the cup rim due to air pressure.

The stacker tube slopes downwardly and then bends upwardly at a bottom point 28 and extends from there to a discharge point (not shown). The upward portion of the stacker tube provides a downwardly pressing column of nested cups, and hence a back pressure to keep the cups in shape until the glue is set.

The stacker tube is secured to the machine in any suitable manner, such as by brackets 29 and 30, as shown.

Having thus described my invention, I claim:

1. A stacker tube for a paper cup machine comprising a tubular member having one end thereof outwardly flared to receive paper cone cups to be stacked, said tubular member having apertures therein from the exterior to the interior thereof adjacent said flared end.

2. A stacker tube for a paper cone cup machine comprising a tubular member, one end of said member hav-

ing an outwardly flared end subdivided into a group of fingers, said tubular member having apertures therein from the exterior to the interior thereof adjacent said fingers.

3. A stacker tube for a paper cone cup machine comprising a tubular member, a group of fingers at one end of the member, said fingers being outwardly flared, said member having a circumferential row of apertures therein from the exterior to the interior thereof adjacent said fingers.

10 4. A stacker tube for a paper cone cup machine comprising a tubular member, a group of fingers at one end of the member, said fingers being outwardly flared and spaced apart, said member having apertures therein from the exterior to the interior thereof adjacent said fingers.

15 5. In a paper cup machine having a stacker tube, said stacker tube having a receiving end, fingers projecting upwardly and outwardly from said receiving end, said tube having a circumferential row of apertures therein from the exterior to the interior thereof adjacent said fingers.
